PRESSER LIFTER ACTUATING MECHANISM
FOR SEWING MACHINES

Arthur N. Hale, Stratford, Edward L. Koenig, Westport, and William J. Edwards, Stratford, Conn., assignors to The Singer Manufacturing Company, Elizabeth, N. J., a corporation of New Jersey

Application February 27, 1952, Serial No. 273,602

5 Claims. (Cl. 112—237)

1

The present invention relates to sewing machines and particularly to a knee-operated device for raising and lowering the presser mechanism, or what is commonly referred to as a knee-shift. The present invention has for an object to provide such a device that is constructed of simple mechanical expedients which are inexpensive to manufacture and yet durable and dependable in operation, and which can be readily adjusted to fit various types of sewing machines.

Having in mind these and other objects that will be evident from an understanding of this disclosure, a presently preferred embodiment of the invention is hereinafter set forth in such detail as to enable those skilled in the art to readily understand the function, operation, construction and advantages of it, when read in conjunction with the accompanying drawings in which:

Figs. 1 and 2 are front and end elevation views, respectively, of a knee-shift device constructed in accordance with the principles of the present invention, mounted upon a table (partly broken away) and operatively associated with a sewing machine mounted upon the table.

Fig. 3 is a bottom plan view on an enlarged scale of the knee-shift device per se which is included in Figs. 1 and 2.

Fig. 4 is a section view on a larger scale taken substantially along the line 4—4 of Fig. 3, with parts broken away.

In the drawings, the knee-shift device that has been selected for purposes of illustrating the present invention is generally indicated at 1 and is secured to the under side of a table 2 upon which is mounted a sewing machine 3. The machine 3 is substantially the same as that disclosed and claimed in the copending application of Hale, Serial No. 226,082, filed May 12, 1951, and since the particular machine does not constitute a critical element of the invention, it is not deemed necessary to expand this disclosure in relation thereto. It is sufficient for purposes of the present disclosure to point out that the machine 3 includes a bed 4, an upstanding standard 5 and an overhanging bracket arm 6 terminating in a head 7. Journaled for vertical reciprocation in suitable bearings in the head 7 is the usual presser-bar 8, spring biased downwardly and carrying a presser-foot 9 at its lower end. A collar 10 is fixed to the presser-bar 8 and includes a rearwardly extending lug 11 that is adapted to be engaged and raised either by hand by the cam surface of a conventional hand-lever 12 or by a knee-operated mechanism including an arm 13 secured to one end of a rock-shaft 14 suitably journaled longitudinally of the bracket-

2

arm 6. At its end opposite the arm 13, the shaft 14 has secured thereto a rearwardly extending actuating lever 15. A spring 16 acting between the lever 15 and the bracket-arm 6 normally urges the lever 15 upwardly and maintains the arm 13 in engagement with a stop pin 17. A chain 18 is connected to the free end of the lever 15 for actuating the same. Thus it will be seen that, as the chain is pulled downwardly, the presser is lifted from operative position, and as the tension on the chain is relaxed, the presser-foot will return to its normal position under spring pressure.

The knee-operated mechanism for pulling the chain 18 downwardly generally designated at 1, comprises an L-shaped base plate 19 provided with elongated apertures 20 which are adapted to receive screws 21 that secure the base plate to the under side of the table 2. The elongated apertures 20 provide limited lateral adjustment of the base plate relative to the table 2 and consequently to the machine 3. An aperture 22 is punched in the one leg of the L-shaped base plate 19, which aperture is so formed as to leave three ears 23, 24 and 25 which are subsequently bent into planes at right angles to the base plate, as shown in the drawings. Thus the ears 23, 24 and 25 are, in effect, struck up from the base plate 19. The ears 23 and 24 are directly opposed to each other and have bushings 26 secured in suitable apertures therein to provide spaced bearings. A yoke member 27 is pivoted to the base plate 19 by means of a pivot bolt 28 that passes through suitable apertures formed in legs 29 and 30 of the yoke and through the bushings 26. The pivot bolt 28 may be secured in any suitable manner such as having one end headed and the other end upset. Fitted in an aperture 31 which is drilled preferably horizontally in the yoke 27 is one end of a rod 32 that is secured in the desired position by a set screw 33. That portion of the rod 32 that is fitted in the yoke 27 is formed at almost a right angle to the remainder thereof which thus lies in substantially a vertical plane 35 when in normal operating position, and which carries a conventional knee-pad 34 secured to the rod 32 in vertically adjusted position by a set-screw 35. The leg 30 of the yoke member is elongated to form a laterally extending lever 36 including a reduced end portion 37 terminating in a ball 38. Pivotal movement of the yoke 27 about the pivot bolt 28 is limited in the one direction by a raised flat 39 formed on the lever 36 that contacts the base plate 19, and in the other direction by an adjustable stop member 40, U-shaped in cross-section, that is secured to the ear 25 in

vertically adjusted position by a screw 41 fitted in an elongated slot 42 in the stop-member 40 and a tapped hole in the ear 25, which stop-member 40 is adapted to abut against the body portion of the yoke 27.

Punched or struck down from the base plate 19 and depending therefrom are two spaced apart ears 43 having bushings 44 fitted in suitable apertures therein to form spaced apart, aligned bearings for a rock-shaft 45. It will be noted that the shaft 45 extends substantially parallel to the pivot bolt 28 and, thus, at a right angle to lever 36 of the yoke 27. There is provided a partially cylindrical socket member 46 having a transverse shaft receiving bore drilled through one end thereof that slidably receives the shaft 45. The socket member is adjustably secured to the shaft 45 by a set screw 47. One end of the socket member 46 is provided with a hole or socket 48 that slidably receives the ball end 38 of the arm 36. Surrounding the shaft 45 is a spring 49, one end of which engages one of the bearing ears 43 and the other end of which is fitted into an aperture 50 in the socket member 46 to bias the parts into their neutral position as illustrated in Fig. 1 of the drawings. The shaft 45 is provided at one end with a laterally extending arm 51 i. e. oblique or angularly offset with respect to the longitudinal axis of the shaft and having an aperture or eye 52 formed therein to receive the end connecting link of the chain 18.

With reference to Fig. 1 it will be obvious that as an operator places her knee against the knee-pad 34 and presses it and the rod 32 in the direction of the arrow A, the yoke 27 pivots in a counterclockwise manner about the pivot bolt 28, which depresses the ball end 38 of the lever 36 and consequently the socket end of the member 46 is depressed in a clockwise manner about the axis of the shaft 45, rotating the shaft 45 and carrying downwardly the arm 51 connected to the chain 18, thus pulling on the chain and elevating the presser mechanism. When the operator relaxes the pressure on the knee-pad 34, the elements are returned to their neutral position by the spring 49.

An important feature of the present invention is that although there has been provided extremely simple and direct mechanical connections between the elements which provide a rugged and durable construction and permit inexpensive manufacture of the parts and easy assembly thereof, the complete structure is still fully adjustable so that the device may be adapted to use with a great variety of machines. Thus, upon loosening the set screw 47, the shaft 45 and consequently the eye 52 can be shifted to adapt the mechanism for use, with a machine of different size than the one shown. The parts are then locked in their adjusted position solely by tightening the screw 47.

Numerous alterations of the structure herein disclosed will suggest themselves to those skilled in the art. However, it is to be understood that the present disclosure relates to a preferred embodiment of our invention which is for purposes of illustration only and not to be construed as a limitation thereof. All such modifications which do not depart from the spirit of this invention are intended to be included within the scope of the appended claims.

Having thus set forth the nature of the invention, what we claim herein is:

1. A knee-shift device for a sewing machine

comprising a base plate, a pair of opposed apertured ears struck from said base plate, a pivot bolt journaled in said apertured ears, a rod pivoted to said base plate by said pivot bolt, a lever rigidly associated with said rod to be moved thereby upon movement of said rod about said pivot bolt, a second pair of opposed apertured ears struck from said base and providing spaced bearings, a rock-shaft rotatably and slidably journaled in said second pair of apertured ears substantially parallel to said pivot bolt, an arm carried by said shaft and adapted to be operatively associated with the presser bar mechanism of a sewing machine for raising and lowering the same upon oscillation of said shaft, a member projecting substantially perpendicular from said shaft and releasably fixed thereto in adjusted position longitudinally thereof, and a ball and socket joint between said lever and said member.

2. A knee-shift device for a sewing machine as set forth in claim 1 wherein said ball and socket joint comprises a socket member having a shaft receiving bore transversely thereof at one end and a socket formed longitudinally thereof at the other end, a ball fixed to the free end of said lever, and being fitted into said socket, said shaft being rotatably and slidably fitted into the shaft receiving bore, and a set screw for locking said socket member to said shaft.

3. A knee-shift device for a sewing machine comprising a rod adapted to be pivotally carried by a sewing machine support, a shaft adapted to be rotatably carried by said sewing machine support on an axis substantially parallel to the pivotal axis of said rod, a laterally projecting arm on said shaft adapted to be operatively associated with a presser-bar mechanism of a sewing machine for raising and lowering the same upon oscillation of said shaft, and operative connections between said rod and said shaft for oscillating said shaft upon pivotal movement of said rod, said operative connections including a joint comprising an interrelated ball and socket, one of which is carried by said rod and the other of which is carried by said shaft.

4. A knee-shift device for a sewing machine comprising a base-plate, a rod pivotally carried by said base-plate, a lever rigidly associated with said rod to be moved thereby upon movement of said rod about its pivot, a shaft rotatably carried by said base plate and including an arm carried by said shaft and adapted to be operatively associated with the presser bar mechanism of a sewing machine for raising and lowering the same upon oscillation of said shaft, and operative connections including a ball and socket joint between said lever and said shaft for oscillating the shaft upon movement of said lever.

5. A knee-shift device for a sewing machine as set forth in claim 4 wherein said ball and socket joint include an interrelated ball and socket, one of which is secured upon the end of said lever and one of which is releasably secured upon said shaft in adjusted position longitudinally of said shaft.

ARTHUR N. HALE.
